UNITED STATES PATENT OFFICE

JOHN J. HVEEM, OF MAYWOOD, ILLINOIS, ASSIGNOR TO W. H. MINER, INC., OF CHICAGO,
ILLINOIS, A CORPORATION OF DELAWARE

HAND BRAKE

Application filed September 10, 1930. Serial No. 480,853.

This invention relates to improvements in hand brakes.

One object of the invention is to provide a power multiplying hand brake mechanism, including a chain winding element, especially adapted for railway cars, wherein quick release of the brakes is had with free running of the chain winding means, the power multiplication being obtained by worm gear means, and the quick release being effected by separation of the gear members to permit the free rotation of the chain winding means.

A further object of the invention is to provide in a hand brake mechanism of the character indicated in the preceding paragraph a power multiplying means comprising intermeshing worm and worm gear elements, separation of which to release the brakes is effected by simple and efficient manually controlled means, including toggle acting elements.

Another object of the invention is to provide a hand brake mechanism including a chain winding drum and power multiplying worm and worm gear drive means, wherein the pull or tension of the tightened brake chain is employed to separate and disengage the worm and worm gears to effect quick release, locking means being employed to hold the worm engaged with the worm wheel or gear, the chain winding drum being mounted so as to be moved away from the worm by the pull of the chain when the locking means is released by the brakeman, free rotation of the chain winding drum being thus permitted.

Other objects of the invention will more clearly appear from the description and claims hereinafter following.

In the drawings, forming a part of this specification, Figure 1 is a vertical, sectional view through the end wall of a railway car illustrating my improvements in connection therewith, the brake mechanism being shown in side elevation and the operating hand wheel thereof in section. And Figure 2 is a vertical, sectional view corresponding substantially to the line 2-2 of Figure 1.

In carrying out my invention, I employ

a housing within which the operating parts of the brake mechanism are contained, the housing being directly secured to the end wall 10 of the car. The housing comprises a flat, vertical, rear wall 11, spaced, vertical side walls 12 and 13, a top wall 14 and a front curved wall 15. The rear wall 11 is provided with three securing lugs 16-16 for mounting the housing on the end wall 10 of the car, two of the lugs 16 extending laterally from one side and the third lug upstanding therefrom, as clearly shown in Figure 2. The housing is fixed to the end wall 10 of the car by any suitable securing means, four rivets being shown, three of which extend through the lugs 16-16 and 16, and the fourth of which extends through the lower righthand corner of the rear wall 11, as clearly shown in Figure 2. The housing is open at the bottom so as to accommodate the brake chain 17 for movement, the chain being connected to the brake mechanism proper of the railway car in the usual manner. At the top the housing is provided with an offset portion, at the lefthand side thereof, as indicated at 18, this offset portion forming a chamber to house the worm driving member, as hereinafter more fully pointed out. The side wall 12 of the housing is provided with a vertically disposed guide opening 19, which is reinforced by outstanding flange members 20-20 along the top and side edges thereof. As most clearly shown in Figure 1, the flange members 20-20 at the sides of the guide opening project below the bottom of the housing and provide supporting bracket means, for a purpose hereinafter described. At the upper ends, the side flange members have inwardly projecting angular sections for retaining a slide member hereinafter described.

The side flange members also have outwardly projecting arc shaped members 50-50 thereon provided with opposed interior arc shaped guide grooves 51-51, as clearly shown in Figure 2.

My improved hand brake mechanism proper comprises broadly a chain winding drum A; a worm gear B; a worm member C; a hand wheel D; a carrier slide E for supporting the chain winding drum; and a lever operated

toggle mechanism F for actuating the slide and holding the same locked in operative position.

The chain winding drum A is preferably of conical or tapered form, as clearly shown in Figure 2, and has bearing members 21 and 22 at opposite ends thereof. The bearing member 22 is of ball-like shape, as clearly shown in Figure 2, and is rotatably journaled in a sectional socket member 23 formed on the side wall 13 of the housing and projecting outwardly therefrom. The bearing member 21 at the opposite end is of cylindrical form. Between the lefthand end of the chain winding portion of the drum and the bearing member 21, the drum is provided with a disc-like flange portion, which is thickened at the periphery thereof and forms the worm gear member B. The peripheral thickened portion of the worm gear B has the usual worm threads formed thereon. The bearing member 21 of the drum is rotatably supported in the carrier slide E, as hereinafter more fully pointed out. The chain winding drum is also provided with a pair of outstanding lugs 24-24 to which the inner end of the brake chain 17 is secured, a pin or bolt member 25 being employed for this purpose, the same extending through aligned openings in the lugs 24-24 and through the end link of the chain 17.

The worm member C is disposed above the worm gear B, transversely of the axis of rotation of the chain winding drum and is mounted within the offset section 18 of the housing. The worm member C comprises an elongated shaft-like element, on which the worm threads are formed. To the right of the threaded section, as shown in Figure 1, the shaft element has a collar 26, which bears on the front wall section of the housing. Outwardly of the collar 26, the shaft element has a cylindrical bearing portion 27 journaled within a bearing member provided on the front wall of the housing. At the inner end, the worm element C is provided with an enlarged cylindrical bearing portion 28, preferably of at least as great a diameter as the threaded portion of the worm member, the portion 28 being journaled in a bearing opening 29 provided in the rear wall portion of the offset section of the housing, the bearing opening being closed by a cover plate 30 secured by any suitable means such as cap screws 31-31 extending through the cover plate and into the rear portion of the housing. At the outer end, the worm element C is provided with a reduced tapered portion 32 of substantially square cross section, on which the hand wheel D is secured, the hub of the hand wheel being provided with a tapered socket fitting the portion 32 of the shaft and being held on the shaft by means of the usual retaining nut threaded on the extremity of the shaft. The worm element C has

the threads thereof normally in mesh with the threads of the worm gear B, as clearly illustrated in both Figures 1 and 2.

The carrier slide E is in the form of a relatively heavy block having a journal opening 33 therein receiving the cylindrical bearing portion 21 of the chain winding drum A. The carrier or slide E is mounted within the guideway 19 of the housing and has a pair of toggle links 34-34 pivotally connected therewith, the upper ends of the links 34 being provided with pivot openings 35-35, receiving trunnion members 36-36 projecting from opposite sides of the block-like carrier member E. The lever operated toggle mechanism F for actuating the slide E, comprises a toggle lever 37 and further includes the two links 34-34. The toggle lever member 37 is of bell crank form, having an operating handle on the outer end thereof and being pivoted on a supporting bolt 38, which has the opposite ends thereof supported by the bracket-like extensions of the side flanges 20-20 on the housing. The short arm member of the bell crank lever, which is indicated by 39, is pivotally connected to the lower ends of the toggle links 34-34 by means of a pivot pin 40, the arm 39 extending between the two links 34-34. The opposite ends of the pin 40 are guided in the slots 51-51 and inward movement of the pin is limited by the inner end walls of the slots 51-51, and cotter pins 52-52 extending through the slots prevent escape of the pin and limit its outward movement. The links 34-34 fit between the block E and the side walls of the guide opening, so that the block E will be properly guided in a vertical path. As shown most clearly in Figure 2, the toggle mechanism is movable to a position beyond vertical alignment of the three pivot members of the same so that the carrier E will be locked when the gear B and the worm C are in operative engagement. Swinging movement of the toggle links 34-34 and the arm 39 toward the right, as viewed in Figure 2, is limited by engagement of the pin 40 with the shoulders formed by the inner end walls of the slots 51-51, as hereinbefore pointed out. Engagement of the pin 40 with the cotter pins at the outer ends of the slots 51-51 limits movement of the toggle means in the reverse direction.

In tightening the brakes, with the parts in the position shown in Figures 1 and 2, the hand wheel D is rotated in a clockwise direction, thereby effecting rotation of the worm C and the intermeshing worm gear B, thus rotating the chain winding drum A and winding the chain thereon. During this operation, the worm B is held in meshing engagement with the worm element C by the toggle mechanism F, as hereinbefore pointed out. When it is desired to release the brakes, the hand grip portion of the lever 37 is de-

pressed, thereby swinging the bell crank lever so as to move the toggle arm 39 thereof to the left, as viewed in Figure 2, swinging the toggle links 34—34 therewith. The toggle will thus be broken and through the further swinging movement of the lever 37 the carrier E will be moved downwardly so as to disengage the worm gear B from the worm element C. When the members B and C have been completely disengaged, the drum A is free to rotate and the chain will quickly unwind therefrom, thereby releasing the brakes. Movement of the worm gear B away from the worm element C is accommodated by the swinging movement of the chain winding drum on the ball and socket bearing connection thereof provided by the bearing elements 22 and 23. It is further pointed out that due to the tension of the brake chain when tightened and the weight of the chain winding drum A, there will be a tendency of the drum to be pulled away from the worm element C, this action being prevented by the locked toggle mechanism comprising the links 34—34 and toggle arm 39. As will be evident, a slight movement of the operating lever 37 downwardly will bring the pivot member 40 of the toggle mechanism F into alinement with the pivots formed by the pin 38 and the trunnions 36—36, thereby slightly raising the corresponding end of the chain winding drum against the pull of the brake chain. As soon as the toggle links are moved to a position beyond that just described, the toggle mechanism will be broken and the pull of the chain will positively move the chain winding drum away from the worm C and disengage the worm gear B therefrom.

After the brakes have been released, the worm gear B is re-engaged with the worm element C by pulling the lever 37 upwardly, thereby operating the toggle link mechanism to restore the carrier E and the chain winding drum A to their normal position. In restoring the parts to this position, the toggle mechanism is actuated to such an extent as to again lock the same, as clearly shown in Figure 2. As will be evident, the weight of the brake chain together with the weight of the chain winding drum will act to hold the toggle mechanism locked until again released by the brakeman.

I have herein shown and described what I now consider the preferred manner of carrying out my invention, but the same is merely illustrative and I contemplate all changes and modifications that come within the scope of the claims appended hereto.

60 I claim:

1. In a hand brake mechanism, the combination with a chain winding drum; of a gear fixed to the drum; driving means meshing with the gear; manually controlled means for disengaging said gear from said driving

means by movement of said drum and gear away from said driving means and in a direction corresponding to the direction of the pull exerted by the tension of the tightened brake chain.

2. In a hand brake mechanism, the combination with a chain winding drum rotatable about a horizontal axis and having the brake chain connected thereto and depending therefrom; of a worm gear fixed to the drum means for pulling the chain upwardly to tighten the brakes by rotation of said drum including a driving worm member disposed above the drum and normally meshing with the gear to effect rotation of the drum to wind the chain thereon; lever operated toggle means for moving said drum and worm gear toward and away from the worm member; and stop means cooperating with said toggle means, said toggle means normally holding said worm gear engaged with said worm member and having the toggle members thereof locked by engagement with said stop means to hold the parts engaged, said locked condition of the toggle members being broken when the lever mechanism is operated in a direction to separate the worm gear from said worm.

3. In a hand brake mechanism, the combination with a chain winding drum rotatable about a horizontal axis, said drum being pivotally supported at one end; a slide supporting the other end of the drum; a worm gear fixed to said drum; a driving worm member meshing with said worm gear; means connected to said slide for supporting and actuating the same, including a pivoted operating lever having a toggle arm thereon and toggle link means pivotally connected at opposite ends to said toggle arm and slide respectively.

4. In a hand brake mechanism, the combination with a chain winding drum rotatable about a horizontal axis, said drum being pivotally supported at one end; a slide supporting the other end of the drum; a worm gear fixed to said drum; a driving worm meshing with said worm gear; means connected to said slide for supporting and actuating the same, including a pivoted operating lever having a toggle arm thereon and toggle link means pivotally connected at opposite ends of said toggle arm and slide respectively, said toggle link means and toggle arm being movable in one direction to a point beyond straightened condition to lock the worm gear in meshing engagement with the worm; and abutment means cooperating with said toggle link means and arm for limiting movement thereof in said last named direction to effect said locking, and said lever being movable to actuate said toggle links and arm in a reverse direction to break said locking condition and completely disengage the worm gear and worm member to permit free running of the chain wind-

ing drum and quick release of the brakes.

5. In a hand brake mechanism, the combination with a chain winding drum; of a worm gear fixed to the drum; a manually rotatable worm member meshing with the gear; manually controlled means for disengaging said gear from said worm member by movement of said drum and gear away from said worm member and in a direction corresponding to the direction of the pull exerted by the tension of the tightened brake chain.

In witness that I claim the foregoing I have hereunto subscribed my name this 8th day of September 1930:

JOHN J. HVEEM.
